FUELO CORPORATION, OF WASHINGTON, DISTRICT OF COLUMBIA, A CORPORATION
OF DELAWARE.

OIL BURNER.

Application filed May 17, 1927. Serial No. 192,117.

This invention relates to oil burners.

The primary object of the invention is to provide an attachment for the air nozzle of the fan housing for the purpose of preventing the ingress of oil from the oil discharging cup to the confines of the fan housing.

More specifically, the invention comprehends the provision of a bent metallic strip secured close to the periphery of the air nozzle and having its free end extending in a vertical plane in close proximity to the oil discharging cup for the purpose of picking up oil globules dripping from the cup and conveying them downwardly in such a manner that said oil globules will be prevented from entrance to the air nozzle and fan housing.

Fig. 1 designates the top of the oil burner I preferably employ and is a longitudinal view partly in section of the burner with my attachment thereon.

Fig. 2 is a front view of the burner showing improved attachment applied thereto.

Much difficulty has been experienced with oil burners of this type wherein the oil atomizing or discharging cup is fitted within the air nozzle attached to the fan housing for the reason that oil inevitably drips back through the air nozzle to the fan housing with the consequent trouble. To relieve this situation, many arrangements have been resorted to, such as drip pots in the fan housing, all of which have been more or less unsatisfactory in practical usage. My invention primarily consists in providing a bent metallic rod shown generally at 1 having one end thereof attached to the air nozzle 2 as at 3. This can be very expeditiously and economically accomplished without any

special tools or skilled labor. The free portion of this oil collecting rod is illustrated at 4 and extends in a vertical position within close proximity to the periphery of the oil discharging cup 5. It will be apparent that the oil globules dripping, by gravity, from the rotating oil cup, or atomizing cup, will encounter the oil collecting device 4 and will be fed thereby downwardly in a manner to prevent their ingress to the air nozzle

2 and the fan housing 6. Within the fan housing there is provided, as usual with this type of burner, a rotatable fan 7 secured to a driving shaft 8 driven by a motor 9. This motor also rotates the cup 5 to which is supplied, in any suitable manner, the oil to be consumed which is fed as a film outwardly where it meets with the air emitting from the air nozzle caused by the fan blades 7.

It will be observed that the air nozzle 2 terminates short of the oil atomizing cup 5 in order that the collected oil may freely descend without contacting with the periphery of the air nozzle 2.

Having thus described my invention, what I claim as new is as follows:

1. An oil burner comprising a fan housing, an air nozzle secured thereto and projecting outwardly therefrom, a rotatable fan within the housing, a rotatable oil discharging cup within the housing and projecting into the confines of the air nozzle, a motor for simultaneously rotating the oil cup and air fan, said air nozzle terminating short of the outer periphery of the oil discharging cup, a bent wire of substantially V-shaped formation having one end secured to the air nozzle and the other end projecting in a vertical plane in close proximity with the periphery of the oil discharging cup and adapted to convey oil drippings from the oil discharging cup downwardly away from the air nozzle, thereby to prevent the entrance of oil into the confines of the fan housing.

2. An oil burner comprising an air nozzle, means for delivering fuel to said nozzle, a wire of substantially V-shaped formation having one end secured to the air nozzle and the other end projecting in a vertical plane in close proximity to the periphery of the oil discharging means and adapted to convey oil drippings from the oil discharging means downwardly away from the air nozzle, thereby to prevent the entrance of oil into the confines of the fan housing.

In testimony whereof I affix my signature.

REGINALD H. PATTERSON.
